(57) **CLAIM**

The ornamental design for a bottle, as shown and described.

DESCRIPTION

FIG. 1 is a top, front and left side perspective view of a bottle, showing my new design;

FIG. 2 is a right view thereof;

FIG. 3 is a left view thereof;

FIG. 4 is a front view thereof;

FIG. 5 is a back view thereof;

FIG. 6 is a top view thereof;

FIG. 7 is a bottom view thereof; and,

FIG. 8 is a partially enlarged view thereof, taken from FIG.

1.

The broken lines in the figures illustrate the portions of the bottle that form no part of the claimed design. The dot-dash broken lines of FIGS. 1 and 8 represent the boundaries of the partially enlarged views only and form no part of the claimed design.
